Application July 17, 1951, Serial No. 237,093

5 Claims. (Cl. 60—35.54)

The present invention relates to turbo-jet units in which air is by-passed on its way from the compressor to the turbine, for instance for feeding braking nozzles.

It is known that braking nozzles, used for reducing the speed of jet aircrafts, in particular for landing, may be supplied with air collected from the outlet of the compressor. However, if no precautions are taken, by-passing of air from the outlet of the compressor involves serious drawbacks concerning the efficiency of the unit.

The object of the present invention is to provide a turbo-jet unit of the type above described which avoids these drawbacks.

Preferred embodiments of my invention will be herein-after described with reference to the accompanying drawings, given chiefly by way of example, and in which:

Fig. 1 is a diagrammatic sectional view of a turbo-jet unit made according to my invention;

Fig. 2 is a corresponding diagram showing the air distribution, a portion of this view being a section on the line II—II of Fig. 1;

Fig. 3 is a diagrammatic plan view showing air distribution cut-off means in two combustion chambers supposed for the sake of simplification to be located in the same plane;

Fig. 4 diagrammatically shows an automatic air by-pass control device according to my invention;

Figs. 5 and 6 are diagrammatic detail views on a larger scale.

The turbo-jet unit of Figs. 1 to 3 includes nine combustion chambers 2 disposed, along the generatrices of a cone, between compressor 3 and turbine 4.

According to my invention, in order to supply the braking nozzles 17, I provide means for cutting off the supply of compressed air to some of these combustion chambers, means for cutting off the supply of fuel to these chambers, and means for by-passing air from the stream flowing from the compressor toward the turbine.

In the example illustrated by Figs. 1 to 3, it is supposed that three combustion chambers, designated by 2a, 2b, 2c, respectively, are thus brought out of action when the braking nozzles are to be operated.

My device includes, in this embodiment, a set of shutters 5 pivotally disposed between fixed partitions 6 and located ahead of said combustion chambers 2a, 2b and 2c. Fixed partitions 6a, 6b, 6c and 6d, which also cooperate with shutters 5, limit said combustion chambers.

Shutters 5 are actuated through a ring 7 movable on an annular bearing surface 8 fixed on the outer casing of the unit. Between ring 7 and shutters 5 are provided links 9 rigid with the spindles 5a of said shutters 5 and the slotted ends 9a of which engage pins 7a carried by ring 7.

Ring 7 may be operated either manually or automatically. In the example shown, ring 7 is actuated by means of a jack 10 operated by oil under pressure supplied from a valve device 11 manually controlled by the

2

operator by means of a lever L. Oil under pressure from a suitable source enters this valve 11 through a conduit 12 and it leaves it through conduits 13 and 14. This oil is fed to jack 10 through either of conduits 15 and 16 and it escapes therefrom through the other of these conduits.

The means for by-passing air from the stream flowing from the compressor toward the turbine and sending this by-passed air to the braking nozzles 17 include three by-pass pipes 18a, 18b, 18c, starting from the conduit leading from the compressor to said shutters 5, at points located upstream of said shutters, these by-pass pipes leading to a common conduit 19 connected through branch pipes 20 with the braking nozzles 17.

15 The inlet of each of these nozzles 17 is provided with a throttle valve 21. These throttle valves 21 are to be opened when shutters 5 are being closed. Advantageously, the means for controlling shutters 5 and those for controlling throttle valves 21 are interconnected.

20 For this purpose, each of the throttle valves 21 is operated, as shown for one of them, by means of a hydraulic jack 22 supplied with oil in parallel with jack 10, for instance through branch pipes 15a and 16a in communication with pipes 15 and 16 respectively (Figs. 2 and 6).

Fuel is fed to each combustion chamber 2 through a pipe 23 controlled by a valve 24. Valves 24 are, same as throttle valves 21, operated through hydraulic jacks 24a supplied with oil through conduits 15b and 16b connected with distributing pipes 15a, 16a respectively (Figs. 2 and 5).

35 Braking nozzles 17 are to be supplied, simultaneously with compressed air, with fuel fed through pipes 25 controlled by valves 26 respectively. Each valve 26 is operated through a hydraulic jack 26a supplied with oil through conduits 15c, 16c branching off from conduits 15a, 16a respectively.

Advantageously, the turbo-jet unit is provided, in its jet nozzle, with a cone 27 slidable longitudinally in the jet nozzle for varying the outlet section of said jet nozzle. Control of the longitudinal displacements of this cone is preferably interconnected with that of shutters 5. For this purpose, cone 27 carries a nut 28b prevented from rotating about its axis and in mesh with a screw 28a rotatable about its axis but prevented from sliding longitudinally, rotation of this screw being obtained from a shaft 29 actuated by a pinion 30, which may be the gear of a hydraulic motor 31 inserted in the oil circuit constituted by pipes 15d and 16d (Figs. 1 and 2).

45 In the above described example of a device according to my invention, a certain amount of air can therefore be by-passed from the compressor 3 to the braking nozzles 17 by operating lever L to place a given number 50 of combustion chambers temporarily out of action.

55 I may also, according to my invention, vary the relative amount of air which is thus by-passed. This result can be obtained by providing means for bringing the various elements above referred to (such as shutters 5, throttle 60 valves 21, etc.) into any of a plurality of positions intermediate between the fully closed one and the fully open one.

65 However, I consider that it is more advantageous to vary the number of combustion chambers brought out of action, the number of braking nozzles brought into action being simultaneously and correspondingly varied.

70 According to a preferred embodiment of my invention, the supply of air from the compressor to the respective braking nozzles is automatically controlled in response to variations of the compressed air pressure downstream of the compressor, these variations being produced by

the operator by varying the number of combustion chambers that are out of service.

Fig. 4 shows automatic control means complying with this condition. This arrangement corresponds to the case of an airplane provided with four braking nozzles adapted to be operated independently. Fig. 4 shows the means for controlling the feed of air to only two of these nozzles, by means of hydraulic jacks 32a and 32c. The two other nozzles would be controlled similarly.

These jacks are controlled by means of an automatic valve system including a casing 33, a diaphragm 34, a spring 35 and a slide valve 36. One of the faces of diaphragm 34 is connected through a conduit 37 with the space on the downstream side of compressor 3 and is therefore subjected to the pressure of the compressed air, and the other face is subjected to the atmospheric pressure owing to the provision of ports 38. Spring 35 balances the difference between these pressures.

The casing 36a of slide valve 36 is supplied with oil under pressure through a conduit 39. The discharged oil escapes through either of conduits 40 and 41.

Valve 36—36a operates a relay valve device 42, through two conduits 43 and 44.

This relay valve device 42 is supplied with oil under pressure through conduit 45, whereas the discharged oil escapes through either of conduits 46 and 47.

The four braking nozzle control jacks are supplied with oil under pressure respectively through conduits 48a, 48b, 48c, 48d for displacement in one direction and through conduits 49a, 49b, 49c, 49d for displacement in the other direction.

When the operator actuates shutters 5, and for instance when he opens only those corresponding to one combustion chamber, the compressed air pressure on the downstream side of the compressor tends to rise, whereby slide valve 36 moves downwardly. Oil under pressure from conduit 39 is then supplied to cylinder 42 through conduit 43. Piston 42a moves down and causes slide valve 42b to connect conduit 49a with feed conduit 45. The piston of jack 32a is thus moved down, which opens the throttle valve 21 of the corresponding braking nozzle. The throttle valves of the other braking nozzles are still closed.

However, the amount of air by-passed from the downstream side of the compressor causes to restore the downstream compressed air pressure to its normal value. When this value is reached, slide valve 36 cuts off the connection between conduit 43 and the source of oil under pressure (conduit 39). Piston 42a and slide valve 42b remain stationary in the position they now occupy.

If the operator increases the number of combustion chambers placed out of service, piston 42a is again moved downwardly, together with slide valve 42b, thus successively bringing the braking nozzles into action.

When the number of combustion chambers placed out of action is reduced, the operations above described are reversed.

Of course, instead of closing some of the combustion chambers, I might as well reduce the section of flow through all of them.

The advantage of my device is as follows:

Considering the case of a turbo-jet unit working under normal conditions (for instance the pressure on the downstream side of the compressor being 5 kgs. per sq. cm. and the temperature upstream of the turbine 800° C.), calculation shows that with my device, the maximum amount of air that can be by-passed (in the limit case where the propulsion energy of the turbo-jet becomes zero) is about 31% of the air flow rate under normal working conditions, whereas with the conventional arrangement, it was only 22%, which corresponds to a gain of 50% over the results previously obtained. Furthermore, the air by-passed with my device is at the normal pressure existing downstream of the compressor, i. e. 5 kgs. per sq. cm., whereas, with the conventional arrange-

ment it would be only 2.24 kgs. per sq. cm. Thus, the thrust I can obtain by means of the braking nozzles is about one half of the thrust developed by the turbo-jet under normal working conditions, whereas, with the conventional arrangement, it is about one fourth thereof.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. In combination with a turbo-jet unit including a compressor, a turbine, a jet nozzle at the outlet of said turbine, means for driving said compressor operative by said turbine, a plurality of combustion chambers mounted in parallel between the outlet of said compressor and the inlet of said turbine and means for feeding fuel to said combustion chambers respectively, a device for by-passing air under pressure from the outlet of said compressor which comprises means for cutting off the communication between the outlet of said compressor and at least one of said chambers, means for cutting off the fuel feed means of said chamber, conduit means for by-passing away from said combustion chambers that portion of the compressed air fed from the compressor to the combustion chamber so cut off.

2. In combination, on an aircraft, a plurality of braking nozzles, a turbo-jet unit including a compressor, a turbine, a jet nozzle at the outlet of said turbine, means for driving said compressor operative by said turbine, a plurality of combustion chambers mounted in parallel between the outlet of said compressor and the inlet of said turbine, and means for feeding fuel to said combustion chambers respectively, and a device for feeding air under pressure from said compressor to said braking nozzles which comprises means for cutting off communication between the outlet of said compressor and any number of said chambers smaller than the total number thereof, means for cutting off the fuel feed means of said chamber, conduit means for by-passing a portion of the compressed air fed at the outlet of said compressor to said braking nozzle, valve means in said conduit means for controlling said nozzles, means responsive to variations of the pressure at the outlet of said compressor for successively opening said valve means as said outlet pressure rises, and means operatively connected with said valve means for operating said communication cut-off means and said fuel feed cut-off means simultaneously and correspondingly with the working of said valves.

3. In combination, on an aircraft, at least one braking nozzle, a turbo-jet unit including a compressor, a turbine, a jet nozzle at the outlet of said turbine, a cone coaxial with said nozzle slidably therein so that longitudinal movement thereof varies the outlet section of said jet nozzle, means for driving said compressor operative by said turbine, a plurality of combustion chambers mounted in parallel between the outlet of said compressor and the inlet of said turbine, and means for feeding fuel to said combustion chambers respectively, and a device for feeding air under pressure from said compressor to said braking nozzle which comprises means for cutting off communication between the outlet of said compressor and at least one of said chambers, means for cutting off the fuel feed means of said chamber, means for sliding said cone in said jet nozzle to reduce the outlet section thereof, conduit means for by-passing toward said braking nozzle a portion of the compressed air fed at the outlet of said compressor, and means for simultaneously and correspondingly operating the four last mentioned means.

4. In a device as claimed in claim 1, means for varying the outlet section of said jet nozzle, and means respon-

sive to operation of said bypassing means to operate said nozzle section varying means.

5. In a device as claimed in claim 1, having a braking nozzle, said conduit means conducting the bypassed air to said braking nozzle.
